UNITED STATES PATENT OFFICE.

GEORGE E. WARREN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

METHOD OF AND APPARATUS FOR HANDLING WELTING.

Application filed June 27, 1919, Serial No. 307,129. Renewed September 14, 1923.

To all whom it may concern:

Be it known that I, GEORGE E. WARREN, a citizen of the United States, residing at Swampscott, in the county of Essex and State of Massachusetts, have invented certain new and useful Improvements in Methods of and Apparatus for Handling Welting; and I do hereby declare the following to be a full, clear, and exact description of the invention, such as will enable others skilled in the art to which it appertains to make and use the same.

This invention relates to a method of handling stock such as welting in the manufacture of shoes. The invention also relates to apparatus for use in carrying out the above-mentioned method and to an improved article of manufacture resulting from the practice of said method.

The invention is described as practiced in the manufacture of shoes of the class generally known in the art as Goodyear welted shoes. The invention, however, is not to be regarded as limited in its application to the manufacture of this particular class of articles but it may be employed with advantage in the manufacture of leather goods of other classes.

In the ordinary method of handling leather stock such as welting prior to its incorporation in the shoe followed in the manufacture of Goodyear welted shoes, a length of welting consisting usually of substantially 20 yards is laid in a coil or hank and is tied up in this form for storage or transportation. It is customary to transport these hanks in an uncovered condition in which the welting is subject to soiling and injury. When the welting is to be used a day's supply consisting of several hanks or coils is issued to the welt sewing machine operator. Before use the hanks are immersed in water and when they have soaked sufficiently the surplus water is drained off and the hanks are then placed on the bench or on the floor behind the machine and the leading end of one of the hanks is inserted in the welt guide of the machine. Each of these hanks contains sufficient welting for sewing about twenty pairs of shoes of medium size. When the hank from which the welt is being drawn is nearly exhausted

so that there is not enough welting to sew another shoe it is necessary either to splice the end of another hank to the part of the hank left in the machine or to remove the short length of the first hank from the machine and insert the leading end of another hank in the welt guide. In handling welting as well as in handling various other kinds of leather stock which, to avoid confusion, are handled in relatively small quantities, the lack of any means heretofore to prevent the tempered stock from drying out before use has been a serious disadvantage.

Obviously when welting designed to be used in the manufacture of shoes, such as Goodyear welt shoes, is handled in the manner above indicated, the welting applied to successive shoes will vary greatly in condition. The welting which is first used will usually be excessively wet, after which its condition may improve as the water dries from the surface and permeates more evenly the body of the welting, and later it will dry out and become relatively stiff. The condition of the welting is a very material factor in the production obtained from the welt sewing machine. If the welting is too wet the fact annoys the operator and he is apt to work slowly or wait until it is in better condition. When the welting becomes too dry it does not run properly to the machine, particularly at the end of the toe where it often curls up and can be straightened out only with considerable difficulty. The improper condition of certain parts of the welting may interfere with or prevent the proper formation of the seam or the proper attachment of the welting to the shoes and thus result in imperfections in the finished shoes.

When the welting is spliced by the operator the splicing requires considerable skill and care and is often improperly done causing imperfect work. In cases where the welting is not spliced the short lengths of welting containing less than enough for a single shoe left at the end of each hank are usually wasted, thereby adding considerably to the expense of manufacture.

In view of the foregoing, one object of the present invention is to provide a method

of handling leather stock such as welting preliminary to its incorporation in shoes or other articles which will obviate the loss of time, the production of soiled or imperfect work, the waste of stock and other disadvantages incident to such methods heretofore followed.

Another object of the invention is to produce apparatus which may be advantageously employed in carrying out the method above referred to.

A still further object of the invention is to provide a mass of welting so arranged and retained in mass formation as to facilitate treating and handling of the mass and subsequent use of the welting.

With these objects in view the invention consists in the method, the apparatus and the article hereinafter described and particularly defined in the claims.

The invention will be readily understood from the following description taken in connection with the accompanying drawings in which Fig. 1 is a view in front elevation of a welt grooving and beveling machine adapted for use in practising the invention; Fig. 2 is a view in front elevation on a somewhat larger scale of the lower portion of the machine shown in Fig. 1; Fig. 3 is a detail view in sectional elevation of the bag holder with which the welt grooving and beveling machine is provided; Fig. 4 is a view in side elevation partly in section of an apparatus which may be used in practising the invention; and Fig. 5 is a view in side elevation of a package of welting produced by the apparatus illustrated in Figs. 1 and 2 and which is used in practising the invention.

In the present method, when applied in handling strip stock such as welting, a strand of welting preferably of considerable length is arranged in a bunch or mass so that it will run freely therefrom without twisting when withdrawn progressively from the same, and the mass of welting is enveloped by a burlap or other fabric bag or covering. The mass of welting preferably consists of several spliced lengths forming a continuous strand long enough to last for several hours' sewing. For example, the strand may be 300 yards in length which is usually enough for an average day's run of the sewing machine. While the welting in the mass may consist of a hank having regularly arranged coils, provided that the welting will run from the same without tangling, twisting and with very little resistance when progressively withdrawn, it is preferred that the mass shall have no definite or regular arrangement of coils but that the welting in the mass shall be loosely arranged to allow the moistening liquid to penetrate the mass readily and that the mass shall be substantially homogeneous through-

out so that it will not collapse during subsequent handling. The mass of welting may be initially arranged within a container such as a large can having a definite form which will facilitate the transfer of the welting therefrom without disarrangement and then transferred into a burlap or other fabric bag. Preferably, however, the coil or mass of welting is delivered progressively into the fabric bag so as to form the coil or mass of welting initially therein.

Figs. 1, 2, and 3 show an apparatus or mechanism which may be employed advantageously in thus arranging the strand of welting in a mass within the fabric bag. This apparatus as illustrated is embodied in a welt grooving and beveling machine of the type illustrated and described in the application of Alfred R. Morrill, Ser. No. 153,014, filed March 7, 1917, Patent No. 1,309,583, dated July 8, 1919, so that the welting is delivered progressively into the bag as it comes from the welt grooving and beveling mechanism. The welt grooving and beveling mechanism of the machine illustrated has the same construction and mode of operation as the corresponding mechanism of the machine illustrated in said patent. The machine is provided with work supporting and feeding rolls indicated respectively at 2 and 4 which are driven through suitable connections from the main driving shaft 5. The welting is delivered by the rolls 2 and 4 to a welting guide 6 mounted to rotate on a vertical axis within the hollow pedestal 8 forming part of the frame of the machine. The driving connections for the welting guide 6 comprise a bevel gear 10 secured to the upper end of the guide and a bevel gear 12 meshing with the bevel gear 10 and driven from the main shaft 5 through suitable gearing.

The pedestal 8 is mounted on a stand 14 provided with upright supports or legs 16. Between the legs of the stand is secured a bag holder 18 consisting of a sheet metal cylinder adapted to be inserted in the mouth of the bag. The bag for the reception of the welting which is indicated at 20 in the drawing is placed between the legs of the stand 14, and the upper end of the bag is drawn over the lower end of the bag holder so that the bag holder will hold the mouth of the bag distended. In order to hold the bag in position on the bag holder a series of spring clips 22 are secured to the bag holder beneath which the upper margin of the bag may be inserted. With this construction as the welting is delivered progressively to the welting guide by the work supporting and feeding rolls 2 and 4, the welting guide will deposit the welting within the bag in a mass without definite or regular arrangement of coils but giving a twist to the welting during each revolution of the

guide so that the welting will run freely from the mass without tangling or twisting as it is withdrawn progressively therefrom.

Suitable material other than burlap may be used as a container or wrapper for the welting provided that it is adaptable for the further steps of the method, and the wrapping need be in the form of a bag only for convenience. The bag may well be of such a size that the coil or mass of welting fits closely therein so that the bag adequately restrains the welting from disarrangement. After the welting is placed in the bag the mouth of the bag is preferably securely closed so that the welting will be fully protected by the bag during storage or transportation. In order to enable the leading end of the welting to be found readily and without disarrangement of the mass of welting when the bag is opened, the leading end of the welting is located in a predetermined, readily accessible position and is secured in position before or at the time that the bag is closed. Preferably the leading end of the welting is tied up in the mouth of the bag as illustrated in Fig. 5 which shows a bag of welting ready for storage, shipment or other handling.

Several hours before the welting is to be used the coil or mass of welting within the bag is wet, preferably by immersing the bag with the welting therein in water. Then after draining off the surplus water, the bag of welting is set aside and the welting allowed to mull within the bag, the bag restricting the circulation of air through the welting and protecting it from surface drying. At the end of a few hours the water will have uniformly penetrated the entire body of the welting, producing a thoroughly mulled and cheesy condition. When in this condition the welting can be readily pierced by the sewing needle without tearing the fibres of the leather, and can be readily shaped as required in attaching the same to the shoe. The welting is preferably maintained in the bag until it is incorporated in shoes and may thus be kept substantially unchanged in temper for a considerable period.

When the welting in the bag is to be used, the bag with the welting therein is placed in a position convenient to the sewing machine, the bag is opened and the leading end of the welting is inserted in the welt guide of the sewing machine. In order to restrict the circulation of air about the bag and thereby prevent rapid drying of the bag and the contained welting, the bag of welting is preferably inserted before use in a container such as a covered can from which the welting may be withdrawn progressively, while the bag with the mass of welting therein continues to be protected by the container. Fig. 4 illustrates a container which

may be advantageously employed to hold the bag of welting while it is being used. As illustrated in this figure the container comprises a cylindrical can 24 for the reception of the bag of welting having a tapered cover 26 formed at its upper end with an opening 28 for the passage of the welting. The height of the can 24 is preferably such that the upper portion of the bag may be turned back over the rim of the can, as shown in Fig. 4, and the lower portion of the cover is arranged to extend within the bag and is formed with an outwardly projecting flange or shoulder 30 arranged to rest on the bag at the point where the bag passes over the rim of the can to hold the bag in place.

When the welting is treated in accordance with the process above described the welting will be in a uniformly and properly tempered condition when delivered to the sewing mechanism, and having been protected by the bag from disarrangement and tangling during storage, transportation, wetting and other handling will run freely from the coil or mass to the sewing mechanism. Although it is not essential that the bag of welting be placed in a can or other container while it is being withdrawn progressively for use, the employment of such a container is advantageous because of the drying conditions about the machine due to the heating of the machine.

The container or can 24 is not claimed herein, it being the subject-matter of a divisional application, Serial No. 435,911, filed Jan. 8, 1921.

This method of handling welting enables the same to be put up, and used in relatively large hanks or masses, thereby avoiding the frequent delays incident to ordinary methods in which the operator has to replenish or splice the welt after sewing a relatively small number of shoes. It has heretofore been impracticable to handle welt in large hanks on account of the disarrangement of the same produced during transportation, dipping, draining and other handling prior to its use, which results in tangles and snarls when the welt is withdrawn from the hand. The present method also eliminates practically all wastage of welting and there are obviously no imperfect splicings in the welt such as occur in the ordinary methods.

The above method obviously is not limited in its application to the treatment of welting but it may be employed with advantage in the treatment of stock of various kinds used in shoe manufacture. It is therefore to be understood that the term welting where employed in the claims is not to be construed in a restricted sense but that this term may apply to other classes of strip stock than true welting.

- Haying explained the nature and object of the invention, and having fully described the manner in which it may be applied, what is claimed is:
5. 1. That improvement in the art of making shoes which consists in arranging a length of welting in a mass so that it will run freely therefrom without twisting, surrounding the mass of welting by a fabric wrapping, tempering it and withdrawing it progressively from the mass for use while the remaining portion of said mass continues to be protected by the fabric wrapping. 70
  10. 2. That improvement in the art of making shoes which consists in arranging a length of welting in a mass so that it will run freely therefrom without twisting, surrounding the mass of welting by a fabric wrapping, wetting the wrapped welting, and withdrawing the welting progressively from the mass for use while the remaining portion of said mass continues to be protected by the fabric wrapping. 75
  15. 3. That improvement in the art of making shoes which consists in arranging a length of welting in a mass so that it will run freely therefrom without twisting, surrounding the mass of welting by a fabric wrapping, wetting the wrapped welting, maintaining the welting in the fabric wrapping while the welting mulls, placing the milled welting in a casing and withdrawing the welting progressively for use while the remaining portion thereof continues to be protected by the casing. 80
  20. 4. That improvement in the art of making shoes which consists in arranging a length of welting in a mass so that it will run freely therefrom without twisting, surrounding the mass of welting by a fabric wrapping, wetting the wrapped welting, maintaining the welting in the fabric wrapping while the welting mulls, placing the milled welting in a casing and withdrawing the welting progressively for use while the remaining portion thereof continues to be protected by the casing. 85
  25. 5. That improvement in the art of making shoes which consists in arranging a length of welting in a mass so that it will run freely therefrom without twisting, surrounding the mass of welting by a fabric wrapping, wetting the wrapped welting and the mass of welting therein. 90
  30. 6. That improvement in the art of making shoes which consists in arranging a length of welting in a mass in a container so that it will run freely from the stationary mass without twisting, and applying a tempering fluid to the welting and maintaining it in the container to cause the same to mull. 95
  35. 7. That improvement in the art of making shoes which consists in arranging a length of welting in a mass in a permeable wrapping so that it will run freely from the stationary mass without twisting, wetting the welting and maintaining it while in a wetted condition in the wrapping to cause the same to mull, and withdrawing the welting progressively for use while the remainder of the mass of welting continues to be protected by the wrapping. 100
  40. 8. That improvement in the art of making shoes which consists in arranging a length of welting in a mass so that it will run freely therefrom without twisting, maintaining the welting while in a wetted condition in a fabric wrapping to cause the same to mull, placing the milled welting in a casing, and withdrawing the same progressively for use while the remainder of the mass of welting continues to be protected by the casing. 105
  45. 9. That improvement in the art of making shoes which consists in enclosing a mass of welting in an air circulation restricting container, and maintaining the same in the container while the welting is being wetted and while it mulls, and withdrawing it progressively for use while the remaining portion continues to be protected by the container. 110
  50. 10. That improvement in the art of making shoes which consists in placing a mass of welting in a container permeable to a moistening liquid, immersing the container with the welting therein in the moistening liquid, and maintaining the welting in the container while the welting mulls. 115
  55. 11. That improvement in the art of making shoes which consists in arranging a length of welting in a mass so that it will run freely therefrom without twisting, surrounding the mass of welting by a fabric wrapping, wetting the wrapped welting, maintaining the welting in the fabric wrapping while the welting mulls, placing the welting with the wrapping thereon in a casing, and withdrawing the welting progressively for use while the remaining portion continues to be protected by the fabric wrapping and by the casing. 120
  60. 12. That improvement in the art of making shoes which consists in arranging a length of welting in a mass so that it will wet up readily and will run freely therefrom without twisting within a coarse fabric container, maintaining the welting within the container until it is to be used, and withdrawing the same from the container progressively for use. 125
  65. 13. That improvement in the art of making shoes which consists in arranging a mass of welting within a coarse fabric container, wetting and mulling the welting within the container, and withdrawing the welting progressively from the container for use. 130
  70. 14. An apparatus for use in handling welting having, in combination, welt preparing means, a bag holder arranged to hold

5 a bag with its mouth distended, and means for delivering a strand of welting progressively from said preparing means into the bag so that the welting will run freely from the stationary mass without twisting when progressively withdrawn.

10 15. An apparatus for use in handling welting having, in combination, welt-grooving and beveling means, a hollow cylindrical bag holder arranged for insertion in the mouth of a bag to hold the bag with its mouth distended, devices for holding the margin of the bag in position with relation to the bag holder, and means for delivering 15 a strand of welting progressively from said grooving and beveling means through the bag holder into the bag so that the welting will run freely from the stationary mass without twisting when progressively withdrawn.

20 16. An apparatus for use in handling welting having, in combination, a hollow cylindrical bag holder for insertion in the mouth of a bag to hold the bag with its mouth distended, devices for holding the margin of the bag in position with relation to the bag holder, a welting guide arranged to rotate on an axis substantially coincident with the axis of the bag holder, and means 30 for delivering the welting progressively to the welting guide.

25 17. That method of making articles of leather which comprises the steps of placing the leather in a permeable receptacle, tempering it by dipping the receptacle with its contents in a tempering liquid, and then withdrawing the leather as required for use.

30 18. That method of making articles of leather which comprises the steps of preparing leather stock for use in making the articles, placing it in a receptacle which permits access of a tempering fluid to the stock but which prevents such a circulation of air as might dry out stock therein and which 45 protects the stock during shipment and other handling, tempering the stock by applying a tempering fluid to stock in the receptacle, and allowing the receptacle to stand while the stock mulls.

40 50 55 19. That method of making articles of leather which comprises the steps of preparing leather stock for use in making the articles, placing it in a receptacle which prevents such a circulation of air as might dry out stock therein and which protects the stock during shipment and other handling, tempering the stock by applying a tempering fluid to stock in the receptacle, allowing the receptacle to stand while the stock mulls, and withdrawing the stock as required for use while leaving the remainder in the receptacle to prevent drying out.

60 65 20. A package adapted for shipment and subsequent handling comprising leather stock prepared and arranged for use, and a

protective covering therefor in the form of a receptacle permitting access of a tempering fluid but preventing such a circulation of air as would dry out stock tempered in the receptacle.

70 21. As an article of manufacture, a wrapping of material permeable to moisture, and a length of welting arranged within the wrapping and having one end thereof arranged in a definite position with relation to the wrapping.

75 22. As an article of manufacture, a wrapping of material permeable to moisture, and a length of welting arranged within the wrapping to permit the welting to be freely withdrawn progressively from the wrapping without twisting.

80 23. As an article of manufacture, a wrapping of material permeable to moisture, and a length of welting arranged within the wrapping and having one end projecting through an opening in the wrapping.

85 24. As an article of manufacture, a fabric bag, and a length of welting arranged within the bag and having one end projecting through the mouth of the bag, the material at the mouth of the bag being tied about said end of the welting to hold it in place.

90 25. That improvement in the art of making shoes which consists in coiling a length of welting within a fabric bag, and securing the leading end of the welting in a predetermined readily accessible position.

95 26. That improvement in the art of making shoes which consists in feeding a strip of welting progressively into the open mouth of a bag, tying up the leading end of the welting in the mouth of the bag, and closing the mouth of the bag.

100 27. That improvement in the art of making shoes which consists in arranging a length of welting in a loose irregular coil within a bag, and securing the leading end of the welting in a predetermined, readily accessible position.

105 28. As an article of manufacture, a length of welting arranged in a mass so that it will run freely therefrom without twisting, and a fabric wrapping therefor.

110 29. As an article of manufacture, a fabric bag, and a length of welting arranged in mass formation within the bag and having one end projecting through an opening in the bag.

115 30. As an article of manufacture, a fabric bag, and a length of welting arranged in irregularly coiled formation within the bag and having one end projecting through the mouth of the bag, the material at the mouth of the bag being tied about said end of the welting to hold it in place.

120 125 31. That improvement in the art of making shoes which consists in feeding a strip of welting into the mouth of an open bag, twisting the welting strip as it is being fed,

tying up the leading end of the welting in the mouth of the bag; and closing the mouth of the bag.

32. That improvement in the art of making shoes which consists in supporting a flexible bag in upright position and holding the mouth of the bag distended to receive a strip of welting, feeding the strip of welting progressively into the distended mouth of the bag, guiding the welting while it is being

fed so that it will arrange itself in loose irregularly coiled mass formation within the bag, closing the mouth of the bag upon the end of the welting leading from the top of the mass therein, and tying the mouth of the bag to hold it closed and to retain said end of the welting in a position readily accessible from the exterior of the bag. 15

GEORGE E. WARREN.
